HAIR CURLING DEVICE

Henry Huber, Woodside, N. Y.

Application August 12, 1937, Serial No. 158,674

7 Claims. (Cl. 132—33)

This invention relates to improvements in hair curling devices.

Objects

- 5 Among the principal objects which the present invention has in view are: to provide a device consisting of a plurality of parts, each part functioning in the operation of and producing ringlets and/or waves in strands of hair; to enable 10 others than skilled operators to operate the device; to provide means for gripping a strand of hair and holding the same to the device while making a ringlet and/or waves; to provide means on the device and transferring the same to the 15 curled strand of hair without first distorting the made ringlet and/or wave; to provide movable means for releasing the completed ringlet and/or wave from the device; to provide a device of lightweight construction and cheap to manufacture; to secure simplicity of construction and 20 operation; and to obtain other advantages and results as may be brought out in the following description.

Drawing

- 25 Figure 1 is an elevation of the assembly of my hair curling and waving device and showing a strand of hair in outline encircling the gripping end;

30 Figure 2 is an end view looking to the left of Figure 1;

Figure 3 is a view similar to Figure 1 and showing the curled strand removed from the device with said curled strand held in position by a clip;

35 Figure 4 is a longitudinal sectional view shown as taken on line 4—4 of Figure 3;

Figure 5 is an elevation of the gripping member with one end broken away;

Figure 6 is an end view of the same;

40 Figure 7 is a cross sectional view shown as taken on line 7—7 of Figure 5;

Figure 8 is an elevation of a slightly different construction of hair waver;

Figure 9 is an end view of the same;

45 Figure 10 is a longitudinal sectional view shown as taken on line 10—10 of Figure 8;

Figure 11 is a side elevation of a clip used for retaining the shape of the ringlet and/or wave when removed from the device; and

50 Figure 12 is an end view of the same.

Description

As will be readily seen in the several views of the drawing, the device 10 may easily be adapted 55 for the producing of ringlets and/or the usual

waves in strands of hair as desired. Heretofore many contrivances have appeared on the market, but none have fulfilled the requirements for individual use and operation. Also, in many instances when an individual desired ringlets and/or waves in the hair it usually required heat to be applied to dampened hair in order that the ringlets and/or waves remain intact. With the present device no heat need be applied and due to the simplicity of its construction and operation minimum time need be utilized for producing a plurality of ringlets and/or waves.

In carrying out the invention, the device 10 preferably may be constructed of a very light but durable material, such as aluminum or the like. 15 The use of such material enables the user to easily manipulate the device when applying it to the hair or upon removal of the same after a curl and/or wave has been set. The present invention is particularly adaptable for home use, and after 20 one curl and/or wave has been set, the user may continue using the device for as many more curls and/or waves as desired. Another feature of the invention is that no heat is required for setting the curls, only a slight damping of the hair being sufficient to retain the curls intact after 25 they have been set and ejected from the curling end of the device.

The curling end of the device 10 may conveniently be designated by the reference numeral 30 11 as consisting of an elongated hollow tubular rod having a U-shaped outer end with outwardly extending prongs 12 and 13 parallel to and spaced apart from each other to provide an opening 14 between them, the purpose of which will herein- 35 after be more fully described. A similar tubular member 15 of a diameter substantially the inside diameter of rod 11 and of a smaller longitudinal length is encased within the said rod 11. The tubular member 15 likewise is provided at its 40 one outer end with a similar U-shaped outer end with a pair of outwardly extending and parallelly spaced prongs 16 and 17 of the same length and shape as the prongs 12 and 13 in rod 11. The said prongs 16 and 17 likewise may be provided 45 with an end opening 18 which normally is in registration with the opening 14 between the prongs 12 and 13 of rod 11 when not in use, or when ejecting a set curl from the device. The inner tubular member 15 in practice is rotatable 50 approximately one-half revolution within the outer rod 11, and when rotated, the prongs 16 and 17 will close the opening 14 between prongs 12 and 13. This procedure is required when desiring to set a ringlet or curl in a lock of hair, 55

the outer end of such lock of hair being placed or inserted between both openings 14 and 18 after which the tubular member 15 is rotated the one-half revolution causing the prongs 16 and 17 to securely grip the lock of hair to the curling end of the device. The device may be then turned by the user to wind that portion of the lock of hair not gripped by the prongs upon the exterior of prongs 12 and 13 thereby 10 setting the ringlet or curl as shown in Figure 1.

Means for preventing more than the one-half revolution of the tube 15 may conveniently be in the form of a spiral groove 19 in approximately the middle of said tube. Means for operating the 15 tube is by utilization of a collar 21 slidable on the outside of rod 11 and a shouldered stud 20 extending through the collar and longitudinal slot in rod 11 with its free end riding within the groove 19. When moving the collar 21 in a forward direction 20 towards the curling end of the device the stud within groove 19 will cause the tube 15 to rotate and the prongs 16 and 17 to close the opening 14 between prongs 12 and 13 in rod 11. A transverse slot 22 in rod 15 towards the end 25 opposite to the end having the prongs permits limited rotation of the said inner tubular member especially when sliding the collar 21 in either direction, it being limited in its movement by a threaded pin 23 held fast with respect to rod 11 with its free end extending therethrough and into the said slot 22. This not only presents a limited 30 movement but also acts as a positive stop of rotation of the inner tubular member 15 and prongs 16 and 17.

35 The invention is further exemplified in Figures 1 to 6 inclusive for obtaining ringlets or curls in the hair. In this showing the reference numerals 25 and 26 indicate a pair of sliding sleeves, of which sleeve 25 for clarity will first be discussed. 40 As shown in Figure 4, said sleeve 25 is attached to but free to slide on rod 11 and in normal position the outer end thereof is in registration with the terminus of the U-shaped openings 14 and 18. In order that the sleeve may be slid on the rod 45 without becoming disengaged therefrom there is a longitudinal slot 27 in both the inner tubular member 15 and rod 11 and preferably parallel with the opening 14 between prongs 12 and 13. The length of said slot 27 preferably is of the 50 same length as the prongs, by virtue of which when sliding the sleeve outwardly to overlie the curling end or prongs, the said sleeve will not protrude beyond the outer edge thereof. A threaded stud 28 extends inwardly through the 55 sleeve and into the slot which acts as a stop when sliding the sleeve either in a forward or rearward direction. The other sleeve 26 preferably is of a length approximately one-half the length of sleeve 25 and likewise is free to slide on sleeve 25 either simultaneously with said sleeve or independently thereof. Normally the sleeve 26 is set back from the forward end of sleeve 25 for purposes to be hereinafter described, and with its inner end in registration with the inner end of 60 sleeve 25. A slot 29 of substantially the same length of slot 27 in tube 15 and rod 11 is provided in sleeve 25 and a stud 30 passing through from sleeve 26 engages the said slot thereby limiting movement of said sleeve 26.

65 In operation and when desiring to set a ringlet or curl in the strand or lock of hair, a spring clip 31 is first applied to encircle the forward portion of sleeve 25 with the outer end of sleeve 26 abutting thereagainst. Said spring clip 31 prefer- 70 ably is of the same longitudinal length as that

of the exposed portion of sleeve 25 in front of the encircling sleeve 26, particularly when the said sleeves are in their normal positions as shown in Figures 1 and 3. The loose end of the strand or lock of hair is then inserted between the 5 openings 14 and 18 of the respective prongs of the outer rod 11 and tube 15. With the lock of hair thus inserted, the collar 21 is then moved forwardly towards the curling end and during its forward movement actuates the inner tubular member 15 its one-half revolution thereby closing the opening 14 and securely gripping the end of hair inserted therein. The hair being securely gripped, the device is then turned clockwise and in turn winds the hair thereon thereby setting 10 the ringlet or curl. With the ringlet or curl set, the sleeve 26 with its end abutting against the spring clip 31 is then moved forwardly on sleeve 25 but independently thereof and against the clip, and slowly disengages the clip from the sleeve 20 25 to frictionally engage the set ringlet or wave on the curling end over the prongs. The clip having been transferred to the hair, the collar 21 may now be returned to its normal position by being moved rearwardly as shown in Figures 1 and 25 3, in which position the gripped end of the loose lock of hair is released. It is preferred that when returning the collar to its normal position the sleeve 25 be moved forwardly simultaneously therewith and to its outermost position. This 30 simultaneous action results in both releasing the gripped end of hair and ejection of the set ringlet with the attached clip 31. The clip 31 on the set ringlet or curl will prevent distortion and keep the same intact until removed therefrom as 35 shown in Figure 3. The respective sleeves 25 and 26 may then be returned to their normal position of Figure 1 and the device again put in use for making other ringlets or curls and/or waves.

40 In the showing of Figures 8 to 10 inclusive I have illustrated a slightly different construction of curling device, which in most respects is substantially similar to the showing of Figures 1 to 7 inclusive. The modified showing is particularly adaptable for setting and obtaining permanent 45 waves in locks of hair, and as shown consists of an outer rod 11' and an inner tubular member 15' as heretofore described. Prongs 32 and 33 in outer rod 11' and prongs 34 and 35 in inner tubular member 15' are similar in construction 50 to the previously described prongs 12 and 13, and 16 and 17, with each said prongs providing similar parallel spaces therebetween. However, it is preferred these prongs be somewhat longer 55 in longitudinal length and terminate adjacent the collar 21'. Actuation of the inner tubular member 15' may be similar to the same member in the preferred construction as by means of spiral groove 19' and with stud 20' riding therein, with the limit of actuation being under influence of transverse slot 22' in member 15' and the stud 23' projecting therein from outer rod 11'. The loose end of the strand or lock of hair as heretofore is inserted through the innermost 60 end of the prongs and upon actuation of the 65 inner tubular member by virtue of stud 20' of collar 21' riding in the spiral groove 19' the hair is securely held fast thereto. With the hair gripped in place, the device may be then turned until the lock of hair completely encircles the 70 curling end at the outer end of the device. Suitable means such as the clip 31 of somewhat larger longitudinal length may then be applied to the curled hair before removal from the device. Also, it may be desired to slightly moisten the 75

hair before removing it from the device, this will aid in retaining the set wave until the clip may be removed. In removing the completed wave, the collar 21' is moved in a rearward direction 5 away from the curling end thereby actuating the inner tubular member 15' and releasing the prongs from gripping the loose end of the hair. Slight pressure may be employed against the set wave at the inner end thereof and with a forward motion the wave easily is removed from the device.

Obviously detail changes and modifications may be made in the construction and use of my improved hair curling device without departing 15 from the spirit and scope of the invention, and I do not wish to be understood as limiting myself to the exact construction or operation shown or described except as set forth in the following claims when construed in the light of the prior 20 art.

I claim:

1. A hair curling device of the character described comprising a pair of tubular members one within the other, cooperating means for actuating one said member with respect to the other said member for securing an end of a lock of hair thereto and enabling the lock of hair to be wound upon the outer member for setting the curl, and means for ejecting the set curl of 30 hair from the said device.

2. A hair curling device of the character described comprising a pair of tubular members one within the other, each said member having cooperating prongs at one end thereof with a space therebetween for reception of the end of a lock of hair, means for actuating one said member with respect to the other said member for securing said end of a lock of hair between the said space of the prongs and enabling the lock 40 of hair to be wound upon the outer of said members for setting a curl, and means for ejecting the set curl of hair from the device.

3. A hair curling device of the character described comprising a pair of tubular members one within the other, each said member having cooperating prongs at one end thereof with a space therebetween for reception of the end of a lock of hair, means for actuating one said member with respect to the other said member 45 for securing said end of a lock of hair between the said space of the prongs and enabling the lock of hair to be wound upon the outer of said members for setting a curl, and a pair of sliding sleeves for contacting and ejecting the set curl 55 of hair from the device.

4. A hair curling device of the character described comprising a pair of tubular members one within the other, each said member having cooperating prongs at one end thereof with a

space therebetween for reception of the end of a lock of hair, means for actuating one said member with respect to the other said member for securing said end of a lock of hair between the said space of the prongs and enabling the lock of hair to be wound upon the outer of said members for setting a curl, and means for ejecting the set curl of hair from the device, and other means for retaining the curl intact.

5. A hair curling device of the character described comprising a pair of tubular members one within the other, each said member having cooperating prongs at one end thereof with a space therebetween for reception of the end of a lock of hair, means for actuating one said member with respect to the other said member for securing said end of a lock of hair between the said space of the prongs and enabling the lock of hair to be wound upon the outer of said members for setting a curl, and a pair of sliding sleeves for contacting and ejecting the set curl of hair from the device, and means on one of said sleeves to be transferred to the set curl before ejecting the said curl.

6. A hair curling device of the character described comprising a pair of tubular members one within the other, each said member having cooperating prongs at one end thereof with a space therebetween for reception of the end of a lock of hair, means for actuating one said member with respect to the other said member for securing said end of a lock of hair between the said space of the prongs and enabling the lock of hair to be wound upon the outer of said members for setting a curl, a pair of sleeves for contacting and ejecting the set curl of hair from the device, means on one of said sleeves to be transferred to the set curl before ejecting the said curl, and said sleeves having means whereby each may slide a limited distance independently of each other.

7. A hair curling device of the character described comprising a pair of cylindrically tubular members of which one substantially fits within the other, both said members having longitudinal slots from one end thereof and corresponding prongs formed as a result of the slots, means for enabling said members to rotate through a limited amplitude with respect to each other and for preventing longitudinal movement of said members with respect to each other, and means slidable and rotatable with respect to one of said members and slidable and rotatable with respect to the other said member whereby sliding said slidable means rotates one member with respect to the other for securing an end of a lock of hair thereto for inserted in said slot between the prongs.

HENRY HUBER.
